UNITED STATES PATENT OFFICE

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE

ADJUSTABLE THROW ECCENTRIC

Application filed November 18, 1931. Serial No. 575,880.

This invention relates generally to new and useful improvements in adjustable throw eccentrics, although the invention is particularly intended for use in sewing machines for varying the feed stroke of the feed dog.

Among the several objects of the invention are to provide an adjustable eccentric assembly wherein the throw of the eccentric may be readily adjusted and wherein the eccentric when adjusted will be retained against accidental displacement; to provide indicating means for easily observing the amount of adjustment given to the eccentric; to provide such an assembly with a comparatively few number of parts; and to provide such a construction which is easy to assemble or disassemble.

With these and other objects in view which will more fully appear, the nature of the invention will be more clearly understood by following the description, the appended claims, and the several views illustrated in the accompanying drawings.

25 In the drawings:—

Figure 1 is a plan view of a construction embodying my invention.

Figure 2 is a longitudinal sectional view thereof,

30 Figure 3 is a right hand elevation of the assembly,

Figure 4 is a sectional view taken on the line 4—4 of Figure 1,

Figure 5 is a sectional view taken on the 35 line 5—5 of Figure 1,

Figure 6 is a left hand end elevation of the assembly,

Figure 7 is a perspective view showing the parts of the assembly in separated relation,

40 Figure 8 is a detail sectional view showing the frictional connection between the driving eccentric and the adjustable eccentric, and

Figure 9 is a detail section showing the 45 pivotal connection between the driving link and the driving eccentric.

Like reference numerals designate corresponding parts throughout the several figures of the drawings.

50 My invention comprises a shaft 5 having

a driving disc 6 mounted thereon and rigidly secured thereto through the medium of an eccentric 7 which is integral with the disc and is fixed to the shaft by a set screw 8. A hub 9 is integral with the disc 6 and extends 55 laterally therefrom in a direction opposite the eccentric 7, and the hub is provided with angular seats 10, 10 which project inwardly from the outer edge thereof. Rotatably mounted on the hub 9 relative to the shaft 5, 60 is a feed adjusting or driving eccentric 11 having a disc 12 integral with the end thereof opposite the driving disc 6. A sewing machine feed or driven eccentric 13 having a bearing opening 14 is fitted about the feed 65 adjusting eccentric 11. Formed in the inner face of the disc 6 along side the feed eccentric 13, is a recess 14^a in which one end of a driving link 15 is pivotally connected to the disc 6 by a pivot screw 16. The other end 70 of the link 15 is pivotally connected to the feed eccentric 13 by a pin 17 which is fixed to the eccentric and projects into a pivot opening 18 formed in the link, thus forming a separable connection between the eccentric 75 and the link. The major axis of the link which extends between the pivots 16 and 18 is positioned tangential to an imaginary circle having for its center the axis of the shaft 5. The recess 14^a is of sufficient depth to permit 80 the link 15 to swing about its pivot 16 for a limited extent. It will therefore be seen that when the disc 12 is turned about the shaft 5, the feed adjusting eccentric 11 will be turned therewith and the feed travel eccentric 13 will be moved radially of the shaft 5 to vary the throw thereof, subject however to a slight distortion due to the 2-point connections 15, 16, 17 between said eccentric and the driving disc 6. 85

The periphery of the adjusting disc 12 is provided with spaced numerals 19, such as "3", "4", "5", etc., which are adapted to indicate the amount of throw of the eccentric 13 in different positions of adjustment of the disc 12. An indicator disc 20 is mounted on the shaft 5 on the side of the adjusting disc 12 opposite the feed travel eccentric 13, and is provided with a hub 21 which fits within the bearing opening of the disc 12 and is pro- 90

vided with longitudinally extending integral lugs 22 which engage in the seats 10 of the hub 9 of the driving disc 6 to thereby retain the indicator disc against rotation relative 5 to the shaft 5. A clamping collar 23 is placed against the outer face of the disc 20 and is secured to the shaft 5 by a set screw 24.

In order to retain the feed travel eccentric 13 in different positions of radial adjustment 10 or throw, I have provided the inner face of the disc 12 with an arcuate series of seats 24^a which register radially with the respective numerals 19, and have mounted in the eccentric 13 a spring pressed plunger 25 which is 15 adapted to engage any one of the seats 24^a and thereby frictionally retain the eccentric in its adjusted position.

The indicator disc 20 is provided with a finger 26 which overhangs the periphery of 20 the disc 12 and cooperates with the numerals 19 to assist the operator in reading the position of adjustment of the feed travel eccentric 13. It will therefore be seen that the indicator finger 26 and the indicator disc 20 25 have a separable interlocking connection 22, 10 with the shaft 5 and consequently said finger and disc are supported on the shaft to rotate therewith.

From the foregoing it will be observed that 30 the parts may be readily assembled or disassembled; that the assembly is composed of comparatively few parts, and is therefore cheap to manufacture.

It is of course to be understood that the 35 details of structure and arrangements of parts may be variously changed and modified without departing from the spirit and scope of my invention.

I claim:—

40 1. In an adjustable throw eccentric, the combination with a shaft, of a driving disc fixed to the shaft, an adjusting eccentric rotatable about the shaft and located along side the driving disc, an adjusting disc fixed 45 to the adjusting eccentric and located at the end thereof opposite the driving disc, a driving eccentric surrounding the adjusting eccentric, a driving link connection between the driving disc and the driving eccentric, and 50 means cooperating with the adjusting disc and the driving eccentric for retaining the same against relative movement in different positions of adjustment of the adjusting eccentric.

55 2. In an adjustable throw eccentric, the combination with a shaft, of a driving disc fixed to the shaft, an adjusting eccentric rotatable about the shaft and located along side the driving disc, an adjusting disc fixed 60 to the adjusting eccentric and located at the end thereof opposite the driving disc, a driving eccentric surrounding the adjusting eccentric, a driving link connection between the driving disc and the driving eccentric, the 65 major axis of the link being positioned tan-

gential to an imaginary circle having for its center the axis of the shaft, and means co-operating with the adjusting disc and the driving eccentric for retaining the same against relative movement in different positions of adjustment of the adjusting eccentric. 70

3. In an adjustable throw eccentric, the combination with a shaft, of a driving disc fixed to the shaft, an adjusting eccentric rotatable about the shaft and located along side the driving disc, an adjusting disc fixed to the adjusting eccentric and located at the end thereof opposite the driving disc, a driving eccentric surrounding the adjusting eccentric, said driving disc being provided with a recess in register with the driving eccentric, a driving link located in said recess and having pivotal connections at its ends with the driving disc and the driving eccentric, and means co-operating with the adjusting disc and the driving eccentric for retaining the same against relative movement in different positions of adjustment of the adjusting eccentric. 75

4. In an adjustable throw eccentric, the combination with a shaft, of a driving disc fixed to the shaft, an adjusting eccentric rotatable about the shaft and located along side the driving disc, an adjusting disc fixed to the adjusting eccentric and located at the end thereof opposite the driving disc, a driving eccentric surrounding the adjusting eccentric, said driving disc being provided with a recess in register with the driving eccentric, a driving link located in said recess and having pivotal connections at its ends with the driving disc and the driving eccentric, 80

the major axis of the link being positioned tangential to an imaginary circle having for its center the axis of the shaft, and means co-operating with the adjusting disc and the driving eccentric for retaining the same against relative movement in different positions of adjustment of the adjusting eccentric. 85

5. In an adjustable throw eccentric, the combination with a shaft, of a driving disc fixed to the shaft, an adjusting eccentric rotatable about the shaft and located along side the driving disc, an adjusting disc fixed to the adjusting eccentric and located at the end thereof opposite the driving disc, a driving eccentric surrounding the adjusting eccentric, a pivotal connection between the driving disc and the driving eccentric, the periphery of the adjusting disc being provided with a series of spaced indicating numerals, means co-operating with the adjusting disc and the driving eccentric for retaining the same against relative movement in different positions of adjustment of the adjusting eccentric, 90

110 and an indicator disc mounted on the shaft for rotation therewith and provided with an indicating finger overhanging the 115

120

periphery of the adjusting disc for cooperation with the numerals on the periphery of said disc.

6. In an adjustable throw eccentric, the combination with a shaft, of a driving disc fixed to the shaft, an adjusting eccentric rotatable about the shaft and located along side the driving disc, an adjusting disc fixed to the adjusting eccentric and located at the 10 end thereof opposite the driving disc, a driving eccentric surrounding the adjusting eccentric, a pivotal connection between the driving disc and the driving eccentric, the periphery of the adjusting disc being provided with 15 a series of spaced indicating numerals, the inner face of the adjusting disc being provided with an arcuate series of seats arranged in radial relation with the respective numerals on the disc, a spring pressed plunger mounted 20 in the driving eccentric for cooperation with any one of said seats to frictionally retain the adjusting eccentric and the driving eccentric against relative rotation, and indicating means rotatable with the shaft and cooperat- 25 ing with the numerals on the periphery of the adjusting disc.

7. In an adjustable throw eccentric, the combination with a shaft, of a driving disc fixed to the shaft to rotate therewith and 30 provided with a hub having an angular seat extending inwardly from its outer end, an adjusting eccentric rotatably mounted on the hub, an adjusting disc fixed to the end of the adjusting eccentric opposite the driving disc 35 and provided on its periphery with a series of spaced indicating numerals, a driving eccentric surrounding and fitting the adjusting eccentric, the driving disc having a recess in register with the driving eccentric, a driving 40 link located in said recess and having one end pivotally connected to said driving disc, the other end of the link being provided with a pivot opening, a pin fixed to the driving eccentric and removably fitted in the pivot 45 opening of the link, the major axis of the link being positioned tangential to an imaginary circle having for its center the axis of the shaft, the inner face of the adjusting disc being provided with an arcuate series of seats 50 arranged in radial relation with respect to the numerals on the disc, a spring pressed plunger mounted in the driving eccentric for engaging any one of said seats to frictionally 55 retain the driving eccentric against accidental movement relative to the adjusting eccentric, an indicator disc mounted on the shaft on the side of the adjusting disc opposite the driving eccentric and provided with a hub formed 60 with a longitudinally extending lug having separable interlocking connection with the angular seat of the driving disc hub, an indicator finger mounted on the shaft to move therewith and overhanging the periphery of 65 the adjusting disc for cooperation with the

indicating numerals thereon, and a clamping collar removably fixed to the shaft and bearing against the indicator disc.

In testimony whereof I affix my signature.
CHARLES W. MUELLER.
